UNITED STATES PATENT OFFICE.

WILLIAM GEORGE GASS, OF BOLTON, ENGLAND.

MACHINE-GUN.

SPECIFICATION forming part of Letters Patent No. 729,858, dated June 2, 1903.

Application filed April 7, 1902. Serial No. 101,700. (No model.)

To all whom it may concern:

Be it known that I, WILLIAM GEORGE GASS, a subject of the King of Great Britain and Ireland, residing at Bolton, in the county of Lancaster, England, have invented Improvements in Machine-Guns, of which the following is a specification.

This invention relates to machine-guns, and more particularly to automatic machine-guns in which the pressure of the gases generated in the barrel by the combustion of the explosive material of the cartridge is utilized to effect the actions necessary for reloading and firing.

15 A machine-gun according to this invention is so constructed that the working parts, which are few and simple, can be quickly and readily withdrawn for examination or repair or for enabling the rapid removal of 20 any damaged or defective cartridge, which ordinarily would cause the mechanism to jam. The barrel is or may be provided with means for increasing the area of its surface that is exposed to the air and for causing a current 25 of air to impinge on the barrel, so as to increase the cooling effect.

An automatic machine-gun according to this invention is so constructed that the apparatus by which the automatic motions are 30 obtained can be readily and quickly disconnected and the gun worked at will by hand.

In order that the mechanism may be readily withdrawn, the actuating handle or lever is carried by a block secured to or forming 35 the rear part of a breech-bolt, which slides longitudinally in a guide, said breech block or bolt also carrying the mechanism which actuates the firing-pin contained within it and the devices which withdraw the live cartridges from some kind of feeder and insert 40 them into the cartridge-chamber of the barrel and which extract and eject the empty cartridge-cases. The actuating handle or lever, which travels bodily to and fro, carrying 45 the breech-bolt with it, and also swings about its pivot in locking the breech-bolt in the firing position in an automatic gun, is connected to a spring tending to hold it in the locking position and to a hinged piston 50 or flap that works in a quadrant-shaped or other sector-shaped chamber communicating with an extension of the barrel and that is

moved by the pressure of the explosion-gases therein in such wise as to actuate said handle or lever in opposition to its spring, thereby 55 opening the breech, withdrawing the empty cartridge-case, and placing another cartridge in position for insertion in the barrel during the return movement of the lever and bolt under the action of the spring. 60

In the accompanying drawings, which illustrate one arrangement of machine-gun according to this invention and designed so as to be capable of acting automatically, Figure 1 is a longitudinal section of the gun, the 65 mechanism being shown in the firing position. Fig. 2 is also a longitudinal section, but showing the mechanism at the end of the recoil with the breech wide open and certain parts omitted. Fig. 3 is a plan of the gun 70 with the top covers removed. Fig. 4 is a detail view of a trigger adapted to hold the mechanism in the position shown in Fig. 2 when required. Figs. 5, 6, 7, 8, 9, and 10 are sections on the lines A A, B B, C C, D D, E E, 75 and F F, Fig. 1, respectively. Fig. 11 is a rear end view of the barrel, showing the end cut away to allow the cartridge-carrier to pass. Fig. 12 is a plan of the forward part of the cartridge-carrier with the cartridge 80 shown ready for extraction from a feed-belt. Fig. 13 is a detail view showing in horizontal section part of the cartridge-carrier ready to extract a cartridge from the barrel. Fig. 14 is a plan of a suitable cartridge-feeding mech- 85 anism, and Fig. 15 is a view at right angles thereto. Fig. 16 is a plan of the body into which the barrel is screwed and carrying the sliding breech-bolt, and Fig. 17 is a side view thereof. Figs. 18 and 19 are respectively an 90 elevation and vertical section of a safety-catch. Fig. 20 is a similar view to Fig. 18 of a modified construction of safety-catch, and Fig. 21 is a longitudinal section through a specially-formed sector-shaped chamber con- 95 taining a hinged piston or flap for use when the gun is to fire blank cartridges.

The barrel *a*, which may be thicker than usual, has its rear end screwed into or otherwise secured to a hollow body *b*, on the sides 100 of which are dovetailed projections *c*, that fit into correspondingly-shaped openings *d* in the sides of the housing *e*, and a cross-bolt *f*, on which the gun swings, passes through the

body *b* and the sides of the housings *e*, which are thus secured without bolts to the body. The body *b*, which may be square in cross-section, is bored throughout its length to receive a longitudinally-sliding breech-bolt *g* and is cut away at *h* to allow the cartridges to pass freely through it in a downward direction, the downward passage of each cartridge being effected in two stages between which it is inserted into the barrel, fired, and its empty case extracted, which is then ejected. The breech-bolt *g* is hollow and contains the firing-pin *i*, the body of which is flat and slightly thicker than the diameter of its forward portion or firing-point *j* and slides easily on its edge in the breech-bolt *g*. The lower portion of the gun-body *b* is cut away at *k* and the bolt *g* is formed with a pair of downwardly-extending lugs or ears *ll*, having pivoted between them a trigger or lever *m*, the upwardly-extending part of which is bifurcated and passes into the bolt *g*, where it receives between its jaws *n* the firing-pin *i*, two projections *o*, on which rest in contact with its rear part.

p is the pivot of the trigger, and *q* a firing-spring that encircles a pin *r*, capable of sliding freely in the rear part of the breech-bolt. The pin *r* can be formed in one with the firing-pin *i* or separate therefrom, as required. The front end of the breech-bolt has secured to it a plug *s*, through which the forward portion or point of the firing-pin *i* passes. This plug is formed with flat sides, (see Fig. 13,) so that it is slightly less in width than the diameter of the rim of the cartridge, and the top edge of the plug is level with that of the cartridge-rim when the cartridge is home in the barrel.

t t are the cartridges. The rear end of the breech-bolt is closed by a block *u*, secured to it by a cotter-pin *v*, so that the firing-spring *q* and other parts are thereby held in place. This block *u* is formed with a downward extension *w*, that is bored so as to slide easily upon a longitudinal slide-bar *x*, secured to the sides of the housing. In the example the bar *x* is fitted into holes in flanges or parts of the housing which are turned in to form the opening *h'* and is secured by a nut, as shown. The actuating handle or lever *y y'*, which is of bell-crank form and can oscillate through a small arc, is mounted on a pin *z*, fixed to the block *u*. This bell-crank lever *y y'*, which is formed of a pair of similar connected plates lying one on each side of the block *u*, carries on its rearwardly-extending arm *y'* a cross-bar *1*, which passes down between inward projections or shoulders *2* on the side housings *e* and the back of the breech-block and locks the latter in the firing position, as shown in Fig. 1. The cross-bar is allowed a little movement in the lever, so as to secure a proper locking action. As will be seen, the opposing surfaces of the bar *1* and the shoulders *2* are curved, so that the bar may easily engage and disengage the shoulders as the lever *y* is turned about its

pivot and so that the said surfaces will touch at points below the level of the axis of rotation of the lever *y*, thus obviating any tendency of the lever to turn into the open position when the cartridge is fired.

Jointed to the trigger or lever *m* is a bar or sear *3*, that extends rearwardly through the part *w* of the block *u* and is pressed upwardly by a spring *4*, secured to the said block. Within the block is an abutment *5*, that is engaged by the end of the sear *3* when the firing-pin *i* has been drawn back.

6 is a tappet arranged in the path of the lower part of the trigger or lever *m*. The tappet *6* is adapted to yield in opposition to a spring *7* and allow the trigger *m* to pass it on the forward movement of the breech-bolt, the lower end of the trigger being suitably formed and the tappet being furnished with a roller *8*, as shown, to facilitate this.

9 is a vertically-movable pin located beneath a projection *10* on the locking cross-bar *1* of the actuating-lever *y* and resting on the bar *3*.

A catch *11* is pivoted to the lever *y*, as shown, and engages with a projection *12* on the extension *w*, so as to prevent the said lever *y* swinging downwardly, so as to bring the locking cross-bar into the locking position and releasing the firing-pin until the parts have arrived at the required position, when the said catch is disengaged by a pin *13*, that is fixed to the housing *e* and is adapted to force down the free end of the catch *11* when the latter comes in contact with it. *11a* is a spring tending to hold up the catch *11*.

Attached to the upper end of the sliding block by being pivoted easily to it at *14* is the cartridge carrier and extractor. This comprises a solid rear portion *15* and a front spring part formed with two spring sides *16*, having suitably-shaped lips *17*, which pass over the rear end of the cartridge that has been brought into position by a traveling belt or hopper or other feeding device, such as hereinafter described. Suitably-shaped internal guide-grooves *18* in these lips receive the rim of the cartridge, and the spring of these lips holds the cartridge securely, while at the same time it does not prevent the cartridge moving vertically between them. This carrier has no movement except backward-and-forward movement with the breech-bolt. The spring sides *16* of the carrier may be of T shape, as shown, and extend from a point sufficiently above the barrel to enable them to engage the cartridge presented by the belt or other feeding device to below the center of the barrel, the spring sides lying edgewise, so that the lower parts are disposed on either side of the plug *s*, forming the front end of the breech-bolt. When the gun is in position for firing, Fig. 1, the spring sides fit between two shallow or narrow snugs *19*, which are on the center line of the barrel and formed in the sides of the hole *h* in the body. (See Figs. 13, 16, and 17.) These snugs prevent those

parts of the spring sides which grip the empty cartridge-case opening out when starting to withdraw the cartridge from the barrel. The 5 decrease in width toward the bottom, and the rear wall thereof terminates at the level of the top of the plug s.

Pivotedly connected at 20 to the solid portion 15 of the cartridge-carrier is an arm 21, that is free to be moved about its pivot in a 10 vertical plane by a fixed projection 22 at the forward end of the stroke of the breech-bolt and by a suitable stop 23 at the other. The projection 22 has an inclined surface and extends from one side of the housing, and the 15 arm 21 has a pin 24 projecting laterally, so as to come in contact with the inclined upper surface of the projection 22, and an upwardly-extending part 25, adapted to come in contact with the stop 23. The part 24 is provided 20 with an antifriction-roller, and the stop 23 is capable of yielding in opposition to a spring 26. This arm 21 has a downwardly-bent portion 27 working between the spring-lips 17 of the carrier and adapted to press a cartridge just 25 drawn from the feeder downwardly between the said lips into the right position opposite the barrel, the breech being open during this action. The cartridge thus pressed down forces the spent cartridge-case, which has 30 been extracted from the barrel, out of the carrier. h^2 is a plate which guides the cases to discharge-opening h^1 . Thus the cartridge once seized by the spring-lips 17 is not released until it has been fired, extracted, and ejected 35 from the carrier, its rim remaining in the grooves 18 throughout.

29 is a pin projecting on one side of the lever y , and 30 is a fixed abutment on the side of the housing against which after the backward 40 oscillation of the lever y has raised the locking cross-bar 1 until it is nearly clear of the fixed shoulders 2 the pin 29 bears.

w^* is a stop which limits the movement of the lever.

45 The side housings are formed of flat plates, having dovetailed recesses 31, in which correspondingly-formed parts of the shoulders 2 fit. The recesses 31 are longer than the projecting portions of the shoulders 2, so that 50 the said projecting portions can be inserted into the widest parts of the recesses and the shoulders secured in place by sliding their projecting portions backwardly into the narrower parts of the recesses, the portion of the recess that is not filled up by the projecting portion of the shoulder being inclosed by part of the shoulder itself, which is prevented from being displaced by a suitably-secured packing-piece. These shoulders require to 55 be hardened, and with this construction the housing-plates can be made of mild steel of a different temper to the locking-shoulders. In some cases, however, the locking-shoulders 2 may be formed as parts of the body of the gun. The housing is provided with a cover 60 32, the rear end of which is hinged at 33 to the side housings or plates e. The cover is

held down by a suitable spring-catch (not shown) at the front. The bottom of the housing is closed by a flanged plate 34, hinged at 70 35 to the side housing-plates, and the back is closed by a plate 36, jointed at 37 to the plate 34 and provided at its free end with a suitable spring-catch 38, that engages projections 39 on the housings e, and thus holds both bottom and back closed. The catch 38 may be arranged inside instead of outside the housing. A handle 40 to hold and direct the gun is attached to the back cover-plate 36, and on the inside of it is a socket 41, which receives 80 the end of the bar x , on which the block w slides. The socket is provided with a rubber buffer 42 or a spring. Projections 36 $\times$ on the housings enter recesses in the plate 36 and prevent its weight being thrown on the 85 catch 38.

In order to obtain the required backward motion of the actuating-lever y automatically, on the muzzle of the gun is arranged an extension 44, which is bored out to a diameter slightly in excess of the largest diameter over the rifling of the barrel. This gives a free passage for the bullet. This extension is secured to the barrel in any convenient way—for instance, by screwing it thereon— 90 its threaded portion being split at 45 and provided with a transverse clamping screw or bolt 46. With the bore of this extension an approximately quadrant-shaped chamber 47 communicates by a passage 48, formed by 100 cutting away the extension to an approximately circular curved form at right angles to the bore of the extension and the highest point of which is at about the axis of the said extension. The side plates of the chamber 105 are afterward put on and secured by brazing, electric welding, or other suitable means. The extension and quadrant chamber may be made integral with the barrel; but it is more convenient to make them separate. 110 This chamber has in it a piston or flap 49, mounted at its rear part on a transverse hinge 50, its free forward edge moving closely against but not touching the curved wall 51 of the chamber. The top of the hinged piston 115 is made with serrations, pockets, or projections, so as to form a toothed surface, against which the issuing gases act, and thus start the outwardly-swinging movement of the piston 49, the completion of whose movement is effected by the expansion of the gases in the quadrant-shaped chamber 47, which is below the axis of the barrel. The serrations, pockets, or projections while not absolutely necessary are advantageous. The hinged 120 piston 49 is coupled by a connecting rod or link 52 to the actuating lever or handle y . 53 is a spring that tends to hold the said lever or handle and the whole mechanism in the firing position shown in Fig. 1. This motor-spring may conveniently be a tension-spring, attached at one end to the housing by a bolt 54 and nut 55 and at the other end to the lower part of the actuating lever or handle. 130

The tension of the spring can be regulated by the external nut 55. The lever or handle *y* is provided with a transverse pin or bar 56, and the end of the rod or link 52 is formed on its upper part with a recess 57, adapted to receive the said pin. The spring 53 is connected to the lever *y* by a T-shaped link-piece 58, which can be passed between the side plates forming the lever *y* and then turned so that its head will engage in recesses 59 in the rear sides of the side plates of the lever. The link-piece 58 is so arranged that it then also acts to keep the connecting rod or link 52 raised and in engagement with the pin 56 in the lever or handle. The link-piece 58 is provided, when necessary, with a suitable spring-catch, so that it cannot accidentally come out of the slot when firing. The said lever or handle extends through a slot in the bottom plate 34 of the housing, so that it can be drawn back by hand to commence firing, or to enable the gun to be worked by hand when the automatic gear is disconnected. When it is desired to render the gun non-automatic, the motor-spring 53 and the connecting rod or link 52 are disconnected, and the latter is drawn to its most rearward position and held there by a suitable spring 60 or a catch, so that the hinged piston 49 will be in a position where it will not be acted on by the gases and the gun can be worked by hand. In some cases only the connecting rod or link is disconnected.

62 is a suitable trigger-catch pivoted to the bottom housing 34, by which the lever *y* can be engaged and the mechanism thus held with the breech open. This trigger-catch 62 is held back out of action while continuous firing is taking place by means of an external finger-loop 63 and can be fixed back for hand-firing by engaging the loop with a hook 64.

In the side housing *e* is fitted a safety-catch, such as shown in Figs. 18 and 19 or in Fig. 20, by which the breech-locking cross-bar 1 is prevented going into place and the action of the gun stopped even with a loaded cartridge in position. The safety-catch comprises a sliding plate 65, having an external knob 66 and an internal pin 67, which when in one position extends beneath the cross-bar 1 when the breech-bolt has moved forward to the end of its stroke and prevents said bar moving down into the locking position. As the locking cross-bar cannot now complete its movement, the firing-pin is not released. The plate 65 may have a horizontal motion, Figs. 19 and 20, or a swinging motion, Fig. 21.

68 is a flexible belt carrying the cartridges *t* and passing through a frame 68^a. 69 is a cross-slide provided with hanging pawls 70 and reciprocated by the movement of the breech-bolt *g* by means of a rod 71 and bell-crank lever 72. The rod 71 has a downwardly-bent end which extends between two pins 20 and 74, projecting laterally from the solid part 15 of the cartridge-carrier, so that as the latter moves to and fro the rod 71 is

also moved. The pawls 70 are adapted to engage the cartridges *t* when the slide 69 moves in one direction, and 75 represents detents provided in the frame 68 to prevent the band of cartridges slipping back when the slide moves in the reverse direction. 68*, Fig. 1, is the hinged cover of the feeding device. A wheel-feed worked in a similar manner could be used, or the cartridges could fall by gravity into position from a hopper instead of the slide arrangement described. The cartridge-feeding arrangement is carried on a vertical pin 76, secured to the side of the housing, so that it can be easily swung out of the way without becoming detached from the gun, and is secured by a suitable catch 77 when in place.

For the purpose of causing air to travel on to the barrel of the gun for cooling purposes on the connecting rod or link 52 are secured suitably-shaped fanners 79, which fanners may comprise transverse pieces of metal of inverted-V shape in cross-section.

80 is a housing or shield that is open top and bottom, directs the air moved by the fanners onto the barrel, and the heat from the barrel causes a further draft up through said housing. These housings for the barrel are secured in a similar manner to the main housings by wedge or dovetailed projections and one cross-bolt. The housings may be formed in one instead of two pieces, if desired. In order that the air may act with the greatest effect on the barrel, it is inclosed in a closely-fitting metallic tube 81, preferably of copper on account of its higher conductivity, the tube being perforated, as shown, so as to increase its cooling-surface.

The automatic action of the gun is as follows: Assuming the mechanism to be in the position shown in Fig. 1, the firing-pin *i* having just struck the cap of the cartridge that is within the barrel *a*, the explosion of the cartridge will drive the bullet forward, and as it passes through the extension 44 a portion of the explosion-gases moves in a downward and forward direction in contact with the upper surface of the hinged piston 49 and starts its turning about its hinge, which turning movement is then caused to continue by the expansion of the gases in the quadrant chamber 47, the hinged piston being thereby driven downwardly and backwardly until it assumes a position in which its free edge has cleared the chamber, whereupon, free egress having been allowed for the expanding gases, movement of the piston ceases. The movement of the piston is communicated, through the connecting rod or link 52, to the actuating lever or handle *y*. The lever *y* is swung back about its pivot until its pin 29 bears against the abutment 30, whereupon the bar 1 being then above the shoulders 2 the breech-bolt *g* is started moving backwardly. Thus the abutment 30 then becomes the fulcrum of the lever, which then acts on the bolt *g* at a mechanical advantage, owing to the positions

of the pin 29 and the pivot z . This movement withdraws from the band 67 the cartridge t the rim of which is gripped by the upper part of the spring sides 16 of the cartridge-carrier and also withdraws from the barrel a the empty case of the cartridge just fired, whose rim will be gripped by the lower part of the spring sides 16. When the lever y can turn no farther about its pivot z , it and the breech-bolt are moved back bodily. During the backward movement of the breech-bolt the lower part of the lever m comes into contact with the tappet 6 and is thereby tripped in such wise as to draw back the firing-pin i and compress the spring q until the free end of the sear 3 moves from beneath the abutment 5, whereupon the spring 4 lifts the bar into engagement therewith, the parts then being in the position shown in Fig. 2. Meanwhile the part 25 of the ejecting-arm 21 has come into contact with the yielding stop 23, and the part 27 has thereby been forced downwardly. This presses the cartridge just drawn from the feeder into a position opposite the barrel, and the said cartridge forces the empty case before it out of the carrier-arms 16. The return movement of the breech-bolt and other parts is effected by the motor-spring 53 acting through the lever y , the cross-bar 1 of which slides upon or above the upper surfaces of the shoulders 2 until the breech-bolt and the live cartridge are home. The cross-bar 1 will then have just cleared the shoulders, and the catch 11 having been released by the pin 13 the lever will be pulled down, so that the cross-bar 1 comes in front of the shoulders 2, so as to lock the bolt. This locking movement of the lever causes the projection 10 to force down the pin 9, and thereby release the sear 3 from the abutment 5 and allow the spring q to drive forward the firing-pin and fire the cartridge that has been inserted in the barrel by the forward movement of the breech-bolt. The forward movement will cause the arm 21 to be raised by its pin 24 acting on the inclined projection 22 and will cause the upper part of the arms 16 to spring over and grasp the rim of a fresh cartridge presented to it by the feeder. When the breech is wide open, or, in fact, at any point, the cartridge-carrier may be lifted up and examined. In case anything sticks it is simply necessary to push the defective cartridge out to make a fresh start. This can be done either by opening the top of the housing or by a suitable device operated from the outside when the breech is wide open.

The construction of the gun is such that by disconnecting the connecting-rod 52, motor-spring 53, and opening the covers or hinged parts 32, 34, and 36 of the housing all the moving parts of the gun can be removed (by pulling back the lever, and so withdrawing the block w from the bar x) and replaced in a few seconds.

To enable the gun to work automatically

with blank cartridges, the end of the barrel may be closed or partly closed by a device such as illustrated in Fig. 21, so as to 70 more or less confine the explosion-gases and cause them to act upon the hinged piston, as hereinbefore described. The device illustrated in Fig. 21 is similar to that illustrated in Figs. 1 and 2 except that there is no outlet in line with the barrel; but the top of the device is curved so as to direct all the gases of explosion onto the piston, the gases escaping from the quadrant chamber at the bottom. In some cases the piston may be made 80 a loose fit, or a reduced outlet-aperture may be formed in line with the barrel.

It will be readily seen that the mechanism hereinbefore described can be operated by other means than the hinged piston device 85 herein mentioned, which may, however, be used to operate other forms of breech mechanism, or the gun can be constructed without the hinged piston device.

It is to be understood that, if desired, a 90 water-jacket can be fitted to the barrel without in any way interfering with the mechanism.

The gun can be carried by any suitable means such as is ordinarily adopted for such 95 guns, and any suitable arrangement of sights can be added.

Some of my improvements may be employed without others, and the details of construction can be varied to suit special requirements. Thus in some cases—for instance, in guns of larger sizes—the form of the passage 48, leading to the chamber 47, may require to be otherwise arranged in order that the gases may act as required upon the piston 100 49 without tending to deflect the bullet. Fig. 22 indicates, by way of example, an arrangement in which instead of a single passage communicating with the under side of the bore of the extension two lateral passages 48 105 are provided.

Instead of a tension-spring a compression-spring may be employed, such a spring encircling a rod attached to the lever y by a sort of link piece or plate 58, one end of the spring 115 acting against a fixed abutment and the other against a nut on the rod.

What I claim is—

1. In a machine-gun, a breech-bolt sliding in a guide, a spent-cartridge-case extractor 120 carried thereby and an actuating and locking lever pivoted thereto, a cross-bar carried by said lever and shoulders, with which when in its locking position, said lever is adapted to engage, a fixed abutment adapted to serve as 125 a fulcrum for said lever when it has been turned about its pivot and become disengaged from said shoulders to release the breech-bolt so that the force applied to the lever will act upon the bolt at a mechanical 130 advantage, thus facilitating the starting of the extraction of the spent cartridge-case, and a stop for limiting the turning movement of the lever so that it will subsequently be

moved back bodily together with the breech-bolt and parts carried by it until the breech is fully open, as set forth.

2. In a machine-gun, a breech-bolt sliding 5 in a guide, a spent-cartridge-case extractor carried thereby and an actuating and locking lever pivoted thereto, a cross-bar carried by said lever and shoulders, with which when in its locking position, said lever is adapted to engage, a fixed abutment adapted to serve as a fulcrum for said lever when it has been turned about its pivot and become disengaged from said shoulders to release the breech-bolt so that the force applied to the 15 lever will act upon the bolt at a mechanical advantage, thus facilitating the starting of the extraction of the spent cartridge-case, a stop for limiting the turning movement of the lever so that it will subsequently be moved 20 back bodily together with the breech-bolt and parts carried by it until the breech is fully open, means for loading and firing the cartridges, means for extracting and ejecting the empty cartridge-cases, and an inclosing 25 casing or housing having hinged portions, all the parts inclosed thereby being so connected and arranged that they can be collectively withdrawn and replaced as set forth.

3. In a machine-gun, breech mechanism 30 comprising a hollow breech-bolt sliding in a guide, a firing-pin capable of longitudinal movement therein, a spring tending to force said pin forward, a cocking-lever pivoted to said bolt and having jaws which extend into it and there engage with lateral projections on the firing-pin, a spring-pressed sear pivoted to said cocking-lever and adapted to engage with an abutment upon the bolt so as temporarily to hold said cocking-lever 35 and firing-pin in the cocked position, a stationary tappet which, during the backward movement of the breech-bolt, acts upon the cocking-lever so that the latter will cock the firing-pin, an actuating-lever carrying a cross-bar and the movement of which into the locking position, causes the cross-bar to release the sear of the cocking-lever, and a catch carried by the actuating-lever and adapted to prevent it assuming the locking 40 position until the breech is closed, as set forth.

4. In a machine-gun, breech mechanism comprising a hollow breech-bolt sliding in a guide, a firing-pin capable of longitudinal 55 movement therein, a spring tending to force said pin forward, a cocking-lever pivoted to said bolt and having jaws which extend into it and there engage with lateral projections on the firing-pin, a spring-pressed sear pivoted to said cocking-lever and adapted to engage with an abutment carried by the bolt so as temporarily to hold said cocking-lever and firing-pin in the cocked position, a stationary tappet which, during the backward movement 60 of the breech-bolt, acts upon the cocking-lever so that the latter will cock the firing-pin, an actuating-lever mounted upon an

extension of the breech-bolt, a tapering pin or cotter securing said extension to the hollow breech-bolt and thus holding the firing-pin and its spring in position, and a catch carried by the actuating-lever and adapted to prevent it assuming the locking position until the breech is closed, as set forth. 70

5. In breech mechanism, the combination 75 with the barrel, a hollow breech-bolt sliding in a guide and a cartridge-feeding device, of a cartridge-carrier having a reciprocatory movement only and provided with spring-arms, which extend from below the barrel to 80 the level of the cartridge-feeding device, one on each side of the forward end of the breech-bolt, formed with guiding-grooves, and adapted, as they move forward with the breech-bolt to move outwardly over the end of and 85 clip the cartridges with the rims thereof in said grooves and retain their hold of them during their withdrawal from the feeding device, loading, extraction from the breech and until final ejection from the gun, as set 90 forth.

6. In breech mechanism, the combination 95 with the barrel, a hollow breech-bolt sliding in a guide and a cartridge-feeding device, of a cartridge-carrier having a reciprocatory movement only and provided with spring-arms, which extend from below the barrel to 100 the level of the cartridge-feeding device, one on each side of the forward end of the breech-bolt, formed with guiding-grooves, of decreasing width toward the bottom and adapted, as they move forward with the breech-bolt to move outwardly over the end of and clip the cartridges with the rims thereof in said 105 grooves and to retain their hold of them during their withdrawal from the feeding device, loading, extraction from the breech and until final ejection from the gun, as set forth.

7. In breech mechanism, the combination 110 with the barrel, a hollow breech-bolt sliding in a guide and a cartridge-feeding device of a cartridge-carrier provided with spring-arms, which extend from below the barrel to the level of the cartridge-feeding device, one on 115 each side of the forward end of the breech-bolt, formed with guiding-grooves, and adapted, as they move forward with the breech-bolt to spring open and clip the cartridges with the rims thereof in said grooves and to retain their hold of them during their withdrawal from the feeding device, loading, extraction from the breech and until final ejection from the gun, and an arm pivoted to it 120 and adapted to be moved downwardly between the spring-arms thereof during the last 125 portion of the backward movement of the breech-bolt for the purpose of moving the live cartridge just withdrawn from the feeder into position ready to be forced into the barrel and of causing it to eject the empty cartridge-case 130 below it, as set forth.

8. In a machine-gun, a breech-bolt sliding in a guide, a spent-cartridge-case extractor carried thereby and an actuating and locking

lever pivoted thereto, a cross-bar carried by said lever and shoulders, with which when in its locking position, said lever is adapted to engage, a fixed abutment adapted to serve as a fulcrum for said lever when it has been turned about its pivot and become disengaged from said shoulders to release the breech-bolt so that the force applied to the lever will act upon the bolt at a mechanical advantage, thus facilitating the starting of the extraction of the spent cartridge-case, a stop for limiting the turning movement of the lever so that it will subsequently be moved back bodily together with the breech-bolt and parts carried by it until the breech is fully open, a motor-spring tending to draw said lever into the locking position, a sector-shaped chamber communicating with an extension of the barrel, a hinged piston or flap working therein and adapted to be actuated by the forward motion of the gases in said extension and their expansion in said chamber, and a rod connecting said piston or flap and the actuating-lever, as set forth.

9. In a machine-gun, a breech-bolt sliding in a guide, a spent-cartridge-case extractor carried thereby and an actuating and locking lever pivoted thereto, a cross-bar carried by said lever and shoulders, with which when in its locking position said lever is adapted to engage, a fixed abutment adapted to serve as a fulcrum for said lever when it has been turned about its pivot and become disengaged from said shoulders to release the breech-bolt so that the force applied to the lever will act upon the bolt at a mechanical advantage, thus facilitating the starting of the extraction of the spent cartridge-case, a stop for limiting the turning movement of the lever so that it will subsequently be moved back bodily together with the breech-bolt and parts carried by it until the breech is fully open, a motor-spring tending to draw said lever into the locking position, a sector-shaped chamber communicating with an extension of the barrel, a hinged piston or flap working therein and adapted to be actuated by the forward motion of the gases in said extension and their expansion in said chamber, and a rod connecting said piston or flap and the actuating-lever, as set forth.

10. In a machine-gun, a breech-bolt sliding in a guide, a spent-cartridge-case extractor carried thereby and an actuating and locking lever pivoted thereto, a cross-bar carried by said lever and shoulders, with which when in its locking position, said lever is adapted to engage, a fixed abutment adapted to serve as a fulcrum for said lever when it has been turned about its pivot and become disengaged from said shoulders to release the breech-bolt so that the force applied to the lever will act upon the bolt at a mechanical advantage, thus facilitating the starting of the extraction of the spent cartridge-case, a stop for

limiting the turning movement of the lever so that it will subsequently be moved back bodily together with the breech-bolt and parts carried by it until the breech is fully open, a motor-spring tending to draw said lever into the locking position, a sector-shaped chamber communicating with an extension of the barrel, a hinged piston or flap working therein and adapted to be actuated by the forward motion of the gases in said extension and their expansion in said chamber, a rod connecting said piston or flap and the actuating-lever and formed with an open jaw or slot on its upper side, a T-shaped link-piece attached to said rod and which can be passed through the lever and is adapted to be then turned so that its head enters a slot in the rear side of the lever and holds up the connecting-rod, and a cross-pin on the lever adapted to be embraced by the jaw or slot in said rod, as set forth.

11. In a machine-gun, the combination with breech mechanism of a hinged piston or flap loosely working in a sector-shaped chamber and formed with tooth-like projections or pockets on a surface that is acted upon by the explosion-gases, as set forth.

12. In a machine-gun, the combination with the barrel and breech mechanism, of a forward extension carried by said barrel and having a passage therethrough for the bullet, a piston or flap hinged at its rear edge in, and freely and closely fitting a sector-shaped chamber in communication with said forward extension, said piston or flap practically closing communication between the chamber and the barrel, when the breech is closed, a lever adapted to actuate the breech mechanism and a connection between said piston or flap and lever, the expansion in said chamber of the explosion-gases continuing to cause movement of the piston or flap until their egress is allowed, substantially as described.

13. A machine-gun comprising a breech-bolt, an actuating-lever, cartridge loading, firing, extracting and ejecting means carried by said bolt, and a hollow body to which the rear end of the barrel is secured, and in which said breech-bolt slides, and side plates forming a housing, said body being formed externally with dovetail projections that fit into correspondingly-formed slots or holes in the side plates and being cut away to permit of the passage of the cartridges through it and to allow of the movements of the various parts during their operation and also to permit of the withdrawal of the breech-bolt and connected parts collectively, as set forth.

14. In a machine-gun, the combination with a sliding breech-bolt, of cartridge feeding mechanism and a rod moved to and fro during the completion of the backward and forward movements of the breech-bolt by tappets thereon and communicating motion to the cartridge-feeding mechanism, as set forth.

15. In a machine-gun, the combination with a sliding breech-bolt, of cartridge-feeding

mechanism comprising a frame through which the charged cartridge-belt passes and having at its upper part a slide carrying a depending pawl adapted to engage the cartridges in the belt and feed the belt forward, a detent adapted to hold the belt during the return stroke of the slide, a bell-crank, one arm of which is connected to said slide and the other to a rod actuated during the completion of the backward and forward movements of the breech-bolt by tappets thereon, as set forth.

16. In a machine-gun, the combination with the casing or housing thereof of cartridge-feeding mechanism pivoted at one side of the casing or housing and adapted to be swung into position or clear of the breech mechanism as required and a spring-catch adapted to hold in position as set forth.

17. In an automatic machine-gun the breech mechanism of which is operated by the pressure of the explosion-gases acting on a piston or the like that is connected to the said mechanism by a longitudinally-movable rod, the combination with the barrel and rod of means adapted to cause air-currents to flow past the barrel each time the rod is moved, and side housings inclosing same but open at top and bottom, as and for the purpose specified.

18. In an automatic machine-gun, the breech mechanism of which is operated by the pressure of the explosion-gases acting on a piston or the like that is connected to the said mechanism by a longitudinally-movable rod, the combination with the barrel and rod, of means carried by the rod adapted to cause air-currents to flow past the barrel each time the rod is moved, and side housings inclosing same but open at top and bottom, as set forth.

19. In an automatic machine-gun, the breech mechanism of which is operated by the pressure of the explosion-gases acting on a piston or the like that is connected to the said mechanism by a longitudinally-movable rod, the combination with the barrel and rod, of pieces of metal of inverted-V section secured to said rod and adapted to cause air-currents to flow past the barrel each time the rod is moved, and side housings inclosing same but open at top and bottom, as set forth.

20. In a machine-gun an inclosing casing comprising side plates and hinged covers

adapted to close in the top, rear end and bottom of said casing or housing, the rear end and bottom plates being hinged or jointed together, and held in position by catches as set forth.

21. In a machine-gun the combination with a sliding breech-bolt of a cartridge-carrier and cartridge-depressing arm pivoted to the said breech-bolt, projections on said arm and fixed abutments adapted to coöperate so as to cause the arm to oscillate about its pivot and thus make room for and depress the cartridge just received by the carrier, as set forth.

22. In a machine-gun, a breech-bolt sliding in a guide, a spent-cartridge-case extractor carried thereby and an actuating and locking lever pivoted thereto, a cross-bar carried by said lever and shoulders, with which when in its locking position, said lever is adapted to engage, a fixed abutment adapted to serve as a fulcrum for said lever when it has been turned about its pivot and become disengaged from said shoulders to release the breech-bolt so that the force applied to the lever, will act upon the bolt at a mechanical advantage, thus facilitating the starting of the extraction of the spent cartridge-case, a stop for limiting the turning movement of the lever so that it will subsequently be moved back bodily together with the breech-bolt and parts carried by it until the breech is fully open, means for loading and firing the cartridges, means for extracting and ejecting the empty cartridge-cases, an inclosing casing or housing having hinged portions, all the parts inclosed thereby being so connected and arranged that they can be collectively withdrawn and replaced, a block secured to the breech-block and having the actuating-lever pivoted to it, a fixed guide-bar upon the rearwardly-extending part of which said block slides and whose rear end is supported by a socket carried by the hinged rear cover or plate of the gun casing or housing, as set forth.

Signed at Bolton, in the county of Lancaster, England, this 24th day of March, 1902.

WILLIAM GEORGE GASS.
